UNITED STATES PATENT OFFICE.

JAMES BARRY, OF GRAFTON, CALIFORNIA, ASSIGNOR OF ONE-HALF TO HENRY WELLER, OF FRESNO, CALIFORNIA.

RAILWAY TIE.

Application filed April 30, 1920, Serial No. 377,882. Renewed October 7, 1922. Serial No. 593,145.

To all whom it may concern:

Be it known that I, JAMES BARRY, citizen of the United States, residing at Grafton, in the county of Yolo and State of California, have invented certain new and useful Improvements in Railway Ties; and I do hereby declare the following to be a full, clear, and exact description of the invention, such as will enable others skilled in the art to which it appertains to make and use the same.

This invention relates to railroad ties and particularly to metallic railroad ties made of two parts, insulated from each other.

An object of the invention is to produce a metallic railroad tie of two parts rigidly interlocked in such manner as to resist relative longitudinal movement of one with respect to the other, and to insulate said two parts from each other.

With the above and other objects in view, the invention consists in the novel features and construction, the combination and arrangement of parts hereinafter more fully set forth, pointed out in the claims and shown in the accompanying drawings, in which—

Figure 1 is a side elevation of a railway tie constructed in accordance with my invention.

Figure 2 is a top plan view,

Figure 3 is a bottom plan view, and

Figure 4 is a detailed longitudinal, sectional view illustrating the manner of connecting the two sections of the tie together.

In carrying out my invention, I provide two separable sections respectively indicated by the numerals 1 and 2 which are suitably connected together at the central portion of the tie. This connection includes a tongue member 3 formed on the section 2 provided at its outer end with an upstanding lip 4. The formation of the tongue 3 at the end of the rail section 2 provides suitable shoulders 5 against which the inner end of the tie section 1 abuts. The section 2 is provided at a point adjacent the inner end of the tongue 3 with an arcuate recess 6, and as it will be noted, the tongue portion at its lower longitudinal edge projects rearwardly and forms one of the side walls of the recess 6, thus providing the shoulders 7 which bear against portions of the tie section 1.

In order to provide for the reception of

the tongue 3 within the inner end of the section 1, a suitable recess 8 is formed, the upper wall of which is inclined inwardly toward the inner end of the recess and at the inner end of this inclined wall the recess 8 is provided with an upward extension 9 which receives the lip 4 on the outer end of the tongue 3 to form a suitable locking connection between the two tie sections. Projecting outwardly from the inner end of the tie section 1 are two spaced arms 10 connected at their outer ends by means of the crossbar 11 which is adapted to be fitted within the recess 6 formed in the tie section 2, which together with the lip 4 locking within the recess 9, will securely retain the two tie sections against any longitudinal movement when placed in position upon the road bed. It will be noted from the illustrations given in Figure 3 that the recess 8 opens through the bottom of the tie section 1 and the lower face of the tongue 3 extends therethrough and is disposed flush with the bottom of the two tie sections so as to provide an even surface at the central portion of the tie when placed in position upon the road bed.

In placing the two tie sections in position, the tongue 3 is inserted into the end of the recess 8, the inclined wall of this recess guiding the tongue so that the lip portion 4 will be guided directly into the extended recess 9 which will permit the tie section 2 to drop downwardly so that the transverse portion 11 will be fitted into the recess 6 and the shoulders 7 rest upon the side arms 10. From this, it will be apparent that if the two tie sections have been placed in position, there will be no chance for longitudinal movement on the part of either of the tie sections with respect to the other. It is preferred that the tie sections be suitably reinforced as shown at 12 at their connecting ends so as to provide for sufficient strength at this point and thereby prevent any breakage on the part of the connecting member. When it is desired to use this tie on roads in which one or both rails serve as conductors of electricity for signaling or other purposes, it is preferred to have a layer of insulating or non-conductive material arranged between the two tie sections as illustrated in Figure 4, said insulating material being indicated by the numeral 13 and being placed in such a position as to

insulate the two tie sections and prevent the electric current from passing from one tie section to the other.

The upper face of each tie section is provided with a transverse rail receiving recess 14 and it will be noted from the illustration given in Figure 2, that these recesses are disposed at oblique angles with respect to the longitudinal center lines of the ties and the 10 said walls of said recesses are provided with shoulder portions 15 arranged at diagonally opposite corners of each recess against which the rail 16 abuts and binds in order to securely retain said rails in position within the 15 recesses. In placing the rails 16 in position within the recesses 14, the rails are first positioned so that they are disposed in alignment with the recesses beneath the base flange of the rails and then positioned within 20 the recesses 14 and when the rails are straightened so that they are disposed directly at right angles with the tie sections, the base flanges of the rails will engage with the shoulders 15 and be disposed beneath the 25 flanges 17 formed through the medium of the undercut side walls of the recesses 14 and by this means the rails 16 are forced into binding engagement with the shoulder portions 15 and in order to provide for additional 30 means for supporting the rails, suitable upstanding flanges 18 are formed upon the outer sides of the recesses 14, said flanges being provided with enlarged end portions 19 which extend upwardly and engage beneath the tread of the rail as illustrated in 35 Figure 1, to thus brace the rail from the outside and also to prevent any separating movement of the rails when placed in their respective positions within the recesses 14.

40 In the general construction of the tie sections as illustrated, they are of I-shaped formation in cross-section and at the point where the recesses 14 are formed, they are reinforced with suitable supporting plates or 45 shelves 19 forming suitable seats for the rails 16, said shelves or plates being supported at each end by means of the bracing ribs 20 which are formed integral with the shelves 19 and with the body portion of the 50 tie sections.

It will be noted that in forming the recesses 14 in the two tie sections, that they are disposed at an angular position with respect to the tie sections and the side walls thereof 55 are undercut to form grooves providing the overhanging flanges 17 which embrace the top portion of the base flanges of the rail to securely retain the rails in position when disposed at right angles to the ties and as 60 certain portions of the base flanges engage with the shoulders 15, it will prevent longitudinal movement on the part of the rail sections. In order to provide further means for preventing movement of the rails 16 after 65 being placed within the recesses 14, the

flanges 18 will engage over the base flanges of the rails and extend upwardly onto the web of the rails to a point beneath the tread portions, thus not only forming a brace to prevent separating movement of the rails, 70 but to form additional binding means adapted to co-act with the binding engagement with the base flanges of the rails on the shoulders 15 of the tie to thus prevent any movement on the part of the rails after being placed within the recesses 14. 75

It will be noted in Figures 1 and 2, that I have provided means for the use of side track rails in connection with my improved tie and to this end, the recesses 21 are formed 80 in the tie adjacent the recesses 14 and are provided with the rail engaging flanges 22. Thus, it will be noted that a side track can be readily positioned with respect to the main track and it is to be understood that the 85 recesses 21 will vary in distance from the main track recesses, according to the curve of the side track to be installed. When the tie is in use on bridges, trestles, or the like, 90 where stringers are used for securing the ties in position, I provide a pair of shoulders upon each of the tie sections and on the bottom thereof, said shoulders being generally indicated by the numeral 23 and disposed in spaced relation as indicated in Figure 1 for 95 engagement upon opposite sides of the stringers to securely retain the ties in position. It will also be noted that the extreme outer end of each of the tie sections is provided with an upstanding flange 24 which 100 will prevent the car wheels from leaving the ties if they should accidentally be caused to leave the rail treads.

What I claim is:

1. A railway tie formed of separable members, one of said members having a recess in the end thereof provided with an inclined wall terminating in an auxiliary recess, a tongue formed on the other member and extending into the first recess, a lip on the 110 tongue for engagement with the auxiliary recess, a recess formed in one face of the second member and a transverse portion carried by the first member for engagement with the recess in the second member to retain said members against longitudinal movement.

2. A railway tie formed of separable members, one of said members having a recess in the end thereof provided with an inclined wall terminating in an auxiliary recess, a tongue formed on the other member and extending into the first recess, a lip on the tongue for engagement with the auxiliary recess, a recess formed in one face of the 120 second member, a transverse portion carried by the first member for engagement with the recess in the second member to retain said members against longitudinal movement and insulating material disposed 125 130

between the two sections, as and for the purpose set forth.

3. A railway tie formed of separable members, one of which is formed with a recess provided with an inclined wall terminating in an auxiliary recess, a tongue formed on the other member and provided at its outer end with a lip for engagement with the auxiliary recess, a recess formed in 10 one face of the second member, spaced arms carried by the first member and a transverse portion secured to the outer ends of said arms for engagement within the recess in the second member to retain said members 15 against longitudinal movement.

4. A railway tie formed of separable members, one of said members having a recess in the end thereof provided with an inclined wall terminating in an auxiliary recess, a tongue formed on the other member, a lip at the outer end of the tongue for engagement with the auxiliary recess, a recess formed in the face of the second member, shoulders formed upon opposite sides of the

25 tongue adjacent the recess, spaced arms carried by the first member for engagement with the shoulders and a transverse portion at the outer ends of said arms for engagement with the recess in the second member, to retain said members against longitudinal 30 movement.

5. A railway tie formed of separable members, one of which is formed with a recess provided with an inclined wall terminating in an auxiliary recess, a tongue formed on 35 the other member and provided at its outer end with a lip for engagement with the auxiliary recess, a recess formed in one face of the second member, spaced arms carried by the first member, a transverse portion secured to the outer ends of said arms for engagement within the recess in the second member to retain said members against longitudinal movement, and insulating material disposed between the two sections, as and 40 45 for the purpose set forth.

In testimony whereof I affix my signature.
JAMES BARRY.
